INVENTOR.

Joseph Hutchins Warren,

By his Attorney,
J. S. Brown.

UNITED STATES PATENT OFFICE.

JOSEPH HUCKINS WARREN, OF BOSTON, MASSACHUSETTS.

TRUSS.

SPECIFICATION forming part of Letters Patent No. 391,099, dated October 16, 1888.

Application filed October 8, 1887. Serial No. 251,831. (Model.)

To all whom it may concern:

Be it known that I, JOSEPH HUCKINS WARREN, a citizen of the United States, residing at Boston, in the county of Suffolk and State 5 of Massachusetts, have invented a new and useful Truss, of which the following is a specification.

My invention relates to improvements in that class of trusses known as the spring-truss, the object and purpose being the maintenance and support of a rupture or hernia in the most efficacious manner with the least complication of mechanism and the slightest discomfort or danger to the wearer. I attain 15 these objects by the use of springs suitably connected together, in combination with a suitable pad or pads in the front and back, with or without a perineal strap, as shown in the accompanying drawings, of which the following is a description.

In the accompanying drawings, Figure 1 represents a front perspective view of the truss complete; Fig. 2, a rear perspective view of the same; Fig. 3, a rear view of the back 25 pads and of the metallic connecting strip uniting the same; Fig. 4, a central longitudinal section of the same; Fig. 5, a rear view of one of the front pads; Fig. 6, a front view of the same; Fig. 7, a longitudinal central section of 30 a self-adjusting connecting device between a front pad and the spring to which it is attached, showing one part in side view; Fig. 8, a central section of a nut and washer shown in connection with one of the attaching-screws.

Similar letters refer to similar parts throughout the several views.

The truss shown as a whole in Figs. 1 and 2 consists, essentially, of two springs, A A, joined together by the intermediate strip, B, and being adjustable thereon, a pair of 40 back pads, C C, attached to this connecting-strip B, and a pair of front pads, D D, attached, respectively, to the free ends of the springs A A directly or by means of the mechanism shown in Fig. 7.

The springs A A consist of thin flat ribbon-like bands of metal of any suitable character, but preferably of steel, said springs being curved to a C shape and attached by their 45 proximal ends to the connecting-strip of metal B, also of steel or other suitable spring metal, by

means of studs or set-screws a a and the movable buttons b, said connecting-strip being slotted at each end, as shown at c c', these slots allowing a certain amount of angular adjustment of the two springs A A, and also allowing an increase or decrease of length of the springs in combination.

The movable button b, attached to the spring A, Fig. 2, engages at its lower extremity by a 60 stud or set-screw, a, with the curved segmental slot c', and is free to move on the spring A and in the said slot c', but when held on the spring A by the set-screw determines the angle which the spring makes with the strip B, 65 this angle being proportionate to the relative positions of the set-screws a a and the stud in the slot c'. This angular adjustment is of especial value in cases of deformity, where one side of the pelvis is higher than the other, or 70 in cases of spinal curvature.

The two springs A A and spring metallic strip B, acting in conjunction, form a continuous spring which exerts constant and uniform pressure upon the hernia, said pressure being 75 transmitted through the front pads, D D, and the connecting mechanism when used, said pressure continuing the same in whatever position or condition the body may be placed.

The connecting-strip B is permanently attached by its opposite and terminal ends or wings to each of the back pads, respectively, as shown in Fig. 2, the central portion of the strip being arched so as to form a saddle which overrides the spine, thus avoiding injury to 80 and chafing of the skin and underlying tissues, which would otherwise occur if the metal strip were contiguous to the body when the truss is in position. This strip is slotted, as shown at c c', for the purpose herein specified. 90

The back pads shown, especially in Figs. 3 and 4, consist of a metal frame, d, of the shape shown in the drawings, this frame being covered with a slightly convex perforated plate, e, of metal, or with wire-gauze f, so attached that 95 its presents its convex surface to the body when in contact with it. Each of these frames is ovoid in shape, the larger end being flattened to be parallel with the spine when in position, said frame being attached by its smaller 100 end to one of the terminal wings of the connecting-strip B by rivets, screws, solder, or

other suitable means. A pair of these pads, the one the counterpart of the other, form the back pad.

Each front pad, D, consists of a metal frame, 5 g, pear-shaped in outline, the one—the right—being the reverse of the other. Each frame is re-enforced by an arch, h, of metal crossing the frame from side to side in the same horizontal plane as the frame, describing an arc of 10 a circle in that plane, having the apex of the frame as a center, said arch being perforated with screw-threaded holes i i, a hole, j, also being bored and screw-threaded near the apex of the frame. The lower portion of the frame 15 is circular in section and receives a ring, E, of metal, which is free to revolve within it in the horizontal plane, but can be immovably fixed within it in any desired position by set-screws. This ring is covered with a plate, G, 20 of perforated metal or piece of wire-gauze, of a convex or other suitable surface, attached to the ring by solder or in any other suitable way, the portion of the frame not filled by the ring being also covered with perforated metal 25 or gauze. These pads thus combined are attached to the terminal ends of the springs A A respectively, the ends being tapered for this purpose to form a curved terminal extension, k, terminating at the arch h of the pad and 30 provided with holes through which screws are passed engaging in the threaded holes j j and one of the series of holes i i, the angle which the pad makes with the spring varying with the hole selected. These perforated 35 sheet-metal or wire-gauze pads allow the escape of perspiration and access of air to avoid irritation of the parts, to maintain a healthy state of the tissue by avoiding overheating, and to allow the topical application of fluid or 40 solid medicaments.

Slight adjustment in the axis of the spring is provided for by the torsion of the spring in the simplest form of the truss; but if greater adjustment is required I make use of the mechanism shown in Fig. 7, consisting of a plate, H, perforated at its center to allow the passage of the screw which attaches it to the spring A, the tail of the spring being cut off when this attachment is used. Ears l are 45 turned up at each side of this plate, which form a joint in conjunction with similar ears, m, turned downward from the sleeve or thimble I, said ears being joined by a cross pin, n, around which a spring, J, is wound, the ends 50 being carried backward and bearing, the one against the sleeve above, the other against the plate below, the tendency of the said spring being to tilt the sleeve upon the pin and constantly separate the rear ends of the plate and 55 sleeve. This sleeve or thimble is made of a section of tubing, and provided, in addition to the downward-projecting ears, with one or more set-screws, o.

The tail-piece cut from the spring A is pro-

vided at its proximal end with a cylindrical 65 stem, P, which fits the sleeve I and is free to revolve in it when not checked by the set-screw, adjustment of the curved arm and pad being thus allowed in the axis of the sleeve. This allows a change in the angle which the 70 pad makes with the body. The spring J also maintains a constant pressure upon the pad, which is thereby enabled to follow every motion of the body and always retain the hernia.

The truss, as a whole, is highly polished and 75 plated with silver, nickel, or gold, or covered with celluloid or hard or soft rubber.

I am aware that prior to my invention trusses have been made with a combination of a spring or of springs with a front and back 80 pad or pads. I therefore do not claim such a combination broadly; but

What I do claim as my invention, and desire to secure by Letters Patent, is—

1. The combination, in a truss, of a slotted and arched strip, B, made of elastic metal, and two springs, A A, bearing the front pads, D D, on their forward ends, curved in form and attached by their back ends to the said strip B by set-screws a a, substantially as described, 90 whereby longitudinal and angular adjustments of the springs are effected, as herein set forth.

2. The combination of a metal frame, d, with a perforated metal plate to form a back pad, said frame and plate being combined with and attached to the strip B, substantially as herein described and set forth. 95

3. The combination of a metal frame, g, a ring, E, and a perforated metal plate to form a front pad, all substantially as herein described 100 and set forth.

4. The combination of a truss-pad frame provided with a perforated attaching-arch, and a perforated truss spring adjustable on the said attaching-arch, substantially as and for 105 the purpose herein specified.

5. The combination of the spring A, having a curved terminal extension, k, and the pad D, having an attaching-screw near one end and a series of screw holes across the main part, also 110 attached to the spring by a screw, substantially as and for the purpose herein set forth.

6. The combination of a frame, g, and a ring, E, adjustable in the frame, said ring being covered with a suitable plate of metal and changeable at will, all specifically and substantially 115 as herein described and set forth.

7. The combination of a plate, H, a joint, O, a sleeve or thimble, J, set-screws o, and a stem, a, free to revolve in said sleeve, all substantially as herein described and set forth. 120

In testimony whereof I have hereunto signed my name in the presence of two subscribing witnesses.

JOSEPH HUCKINS WARREN.
